UNITED STATES PATENT OFFICE

FRED CLEMENS, OF INDIANAPOLIS, INDIANA

AUTOMATIC COURSE COUNTER AND STOP

Application filed May 14, 1927. Serial No. 191,379.

This invention relates to a mechanism for controlling a power operable machine having a moving part for stopping the machine after predetermined movement has occurred.

5 The chief object of the invention is to provide a machine or control mechanism (of the general character indicated) to a knitting machine particularly one for knitting stockings, whereby the knitting machine may 10 be stopped after a predetermined number of courses are formed to insure predetermined length of the stocking.

The chief feature of the invention consists in mechanism for automatically controlling 15 a knitting machine operable thereby, whereby a knitting machine will be stopped after a predetermined number of courses have been knit and which mechanism includes an adjustment for varying the degree of actuation obtainable by an actuating part carried by a moving part of the knitting machine and other adjustments for insuring predetermined operation of the control.

In brief the mechanism includes a ratchet 25 wheel operable with a step-by-step movement from the wrestle bar of a knitting machine, which ratchet through a sprocket gear drives a chain having actuating cams or lugs mounted thereon in spaced relation, the spacing depending upon the number of courses to be knit and the lugs actuating a switch control, the switch controlling the knitting machine.

The full nature of the invention will be understood from the accompanying drawings 30 and the following description and claims:

Fig. 1 is a side elevation of a portion of a knitting machine with the course counter applied thereto. Fig. 2 is a top plan view of the parts shown in Fig. 1.

40 In the drawings there is illustrated a wrestle bar 10 which reciprocates in the actual knitting machine a distance of about fourteen inches. The machine includes a plate 11 which is a part of the framework and 45 also included in the frame of the knitting machine is the transverse frame member 12.

The source of power for the course counter comprises a cam 13 secured to the wrestle bar and movable therewith and having a multiple cam face 14 engageable by a cam fol-

lower or roller 15 rotatably mounted on the end of a lever 16, see Fig. 2. The lever 16 is pivoted at 17 to a bracket 18 secured to the frame plate 11 and the lever at its opposite end terminates in a yoke 19 to which is connected an actuating rod or bar 20. The bracket 18 has a projecting portion 21 which adjustably supports a stop 22. The weight of the several parts and the lever is such as to normally cause the roller 15 to engage the wrestle bar 10 and the face 14. The adjustable stop mechanism 22 is preferably arranged such that the roller does not roll on the wrestle bar but only engages the cam at some portion along its periphery and, of course, leaves the cam at a corresponding point of the cam periphery. The aforesaid adjustment, therefore, determines the amount of throw that the rod 20 is subjected to since the throw of the lever 16 is thus limited or adjusted.

Pivots mounted on the shaft 23 supported in the main bracket or base 24 mounted on the frame member 12 is a lever arm 25 which pivotally supports at 26, a detent or pawl 27, the spring 28 normally maintaining the same in contact with the ratchet 29 also rotatably mounted on the shaft 23 and having the teeth 30 upon its periphery engageable by said pawl. Cam 13 actuates follower 31 and causes lever 16 to tilt which elevates the actuating rod 20 and causes clockwise driving rotation of the ratchet wheel 29, the amount of driving or rotation being determinable by the adjustable stop 22. Secured as at 31 to the ratchet wheel for rotation therewith is a sprocket wheel 32 that meshes with the sprocket chain construction 33 provided with lugs 34 secured thereto in spaced relation. The sprocket chain 33 passes over the pulleys 35 rotatably mounted in the brackets 36 adjustably mounted on the frame member 12. The base 24 also mounts a pulley 35. The positioning of the lugs or cams 34 determines the length of the stocking since the number of courses is determinable by the movement of the wrestle bar which actuates the ratchet to rotate the sprocket gear and drive the chain. Reverse movement of the ratchet is prevented by the base supported

pawl or detent 37 engaging the teeth 30 and being maintained therein by the spring 38. The position of the pawl is adjusted in a well known manner.

5 Also pivotally mounted on the base 24 and at 39 is an arm 40 which carries a cam member 41 adjustably mounted thereon and successively engageable by the cams 34. This engagement causes elevation of lever arm 40 in the free end of which is pivotally mounted a bell-crank lever 42 having on one arm a cam face 43 and a locking groove 44 and on the other a counterweight portion 45, the latter engaging an adjustable stop 46 mounted 10 in the bracket 47 carried by the frame 24. The lower limit of the lever 40 is limited by an adjustable stop 48 also carried by the bracket 47 and a spring 49 is connected to the bracket and the lever arm for normally 15 maintaining the lever arm in its lowered position.

Whenever the cam 34 is caused to ride under the cam 41 the lever arm 40 will be raised from its lowermost position into elevated position. The cam face 43 rides up over the pin 50 carried by a sliding bar 51, in turn connected by a pin and slot connection 52 to an arm 53 mounted on a rock shaft 54. Opposite movement of arm 53 actuates a 20 switch mounted in the casing 55, said switch controlling the main power motor of a knitting machine thereby stopping movement of all of the parts including the wrestle bar 10. After the cam 43 has raised and passed over 25 pin 50 the weight 45 causes the bellcrank lever to tilt clockwise and causes the pin 50 to seat in the notch 44 and the weight of the bellcrank portion 45 is sufficient to cause a sliding and lowering movement of the slide 30 51 to rock the shaft 54 clockwise to open the motor circuit.

It will be apparent, therefore, that the wrestle bar directly controls a rock shaft 54 and that said control is operable only after 35 the wrestle bar has made a predetermined number of reciprocations, the same in turn corresponding to a predetermined number of courses in a stocking, thereby insuring a constant predetermined length stocking. Of course, the spacing of the lugs 34 may be adjusted for any number of courses and the throw of the actuator bar 20 will be adjusted to secure a predetermined operation through 40 the ratchet wheel.

55 The invention claimed is:

1. In a knitting machine or the like, including a switch operating member for controlling the operation of the machine and a machine operable element from which power 60 may be derived, the combination of mechanism for transforming intermittent actuation derived from said machine operable element into progressive rotary motion, a lever pivotally supporting a catch, a plurality 65 of actuating members progressively present

ed by the progressive rotary motion to said lever for tilting the same, and a latch carried by said switch operating member and engageable by the catch for actuating a switch after the lever has been tilted. 70

2. A device as defined by claim 1 characterized by adjustable means for limiting the normal position of said catch. 75

3. A device as defined by claim 1 characterized by adjustable means for limiting the normal position of said lever. 80

4. A device as defined by claim 1 characterized by the addition of independently adjustable means for independently adjusting the normal position of the catch and the lever. 85

5. In a knitting machine the combination of a machine controlling switch including an oscillatable arm normally constrained toward one position, a latch operatively associated with said arm, a catch operatively associated with said latch and including a cam portion and a catch portion, the former permitting movement of the catch relative to the latch for catch positioning and the latter preventing relative movement therebetween, a tiltable support for said catch normally constrained toward positioning the catch in disengagement relative to the latch, and intermittently operable means operable by a movable element of the knitting machine for tilting the catch support for catch and latch engagement and switch actuation. 90 95

6. A device as defined by claim 5 characterized by the intermittently operable means including an endless progressively movable mechanism, a cam carried thereby and arranged to elevate the catch support in the movement of the endless member, a ratchet operatively associated with the endless member for progressively moving the same, and a cam and pawl connection between said ratchet and an operating element of the machine for transmitting the motion of the machine to the endless member for moving the cam into operative position at the predetermined time determinable by the elapsed machine operation. 100 110

In witness whereof, I have hereunto affixed my signature.
